UNITED STATES PATENT OFFICE.

EDWARD NICKERSON, OF BUFFALO, NEW YORK, ASSIGNOR TO HARD MANUFACTURING COMPANY, OF BUFFALO, NEW YORK.

BED-BOTTOM FABRIC.

980,549.

Specification of Letters Patent. Patented Jan. 3, 1911.

Application filed June 25, 1910. Serial No. 568,828.

To all whom it may concern:

Be it known that I, EDWARD NICKERSON, a citizen of the United States, residing at Buffalo, in the county of Erie and State of New York, have invented a new and useful Improvement in Bed-Bottom Fabrics, of which the following is a specification.

This invention relates more particularly to bed-bottom fabrics which are composed of a plurality of wire links connected together in such manner that the fabric is flexible and will fold readily either transversely or longitudinally thereof.

The object of this invention is to provide a fabric of this type in which the links of which the fabric is composed will be of simple and inexpensive construction and can be easily and quickly assembled to form the fabric, and in which the fabric will be strong and durable and at the same time possess the required flexibility so that it can be readily folded without danger of disconnecting the links or causing any undue strain upon the parts thereof.

In the accompanying drawings, consisting of one sheet: Figure 1 is a fragmentary plan view of a bed bottom provided with a fabric embodying the invention. Fig. 2 is a fragmentary perspective view of the fabric, on an enlarged scale. Fig. 3 is a perspective view of a link of modified construction.

Like reference characters refer to like parts in the several figures.

The bed bottom fabric is composed of parallel rows of links A which are arranged end to end longitudinally thereof, and each link is provided at one end with a loop a and at its opposite end with eyes or hooks a', the eyes of each link being adapted to engage in the end loop of the link next adjoining in the row to connect the ends of the links together. The body portion of the links consists of two separate bars or strands 45 of wire a² which extend from the loop a side by side parallel with each other and terminate at their ends in the eyes or hooks a'. Adjacent to their ends the longitudinal links A in all the rows of the fabric except the 50 outside rows are provided with opposite laterally-extending loops a³ which are formed in the bars a² of the links. In the outside rows of links the loops a³ are preferably formed on the inner side of the links only, 55 shown in Fig. 1. The corresponding

longitudinal links in the different rows are connected together by transverse links B which are provided at their opposite ends with hooks or eyes b which engage in the loops a³ of the longitudinal links.

In the construction shown in Figs. 1 and 2, the end hooks b of the transverse links are closed when the links are formed and the loops a³ of the longitudinal links are open at their inner ends. The closed hooks b are of sufficient size to slip over the end eye a' of either of the bars a² of the longitudinal links and slide along the bar through the open end of the loop a³ into engagement therewith. The opening or throat of the loop a³ is preferably contracted so that it is of somewhat less width than the diameter of the wire forming the hook b. The wire of the hook b can be readily forced through the opening into engagement with the loop a³, 75 the wires forming the throat of the loop springing apart sufficiently for this purpose. When once in engagement with the loop a³, the contracted throat of this loop will prevent the hook b from becoming disengaged 80 therefrom and shifting its position on the link A. If desired, the wire forming the hook b may be suitably reduced or flattened at some point to enable the hook to be readily slipped through the throat of the loop. 85 If this is done, the reduced portion of the hook should be formed in a part thereof where it will not be in position to slide out of the throat when once the fabric is formed.

The eyes a' of each longitudinal link are 90 preferably closed when the link is formed and are of sufficient size so that they will slip over either of the corresponding eyes of any one of the other longitudinal links and the laterally-extending loops a³ thereon. 95 This permits the longitudinal links to be easily and quickly assembled, it being only necessary to separate the bars of one link at their free end and then slip both eyes of the other link over the eye of one of the separated strands and slide the same along the strand over the lateral loop into engagement with the end loop of the link. 100 This does away with the necessity of closing the eyes or hooked ends of the links after they are assembled and thus effects a material reduction in the cost of manufacture. When the eyes of one longitudinal link are 105 in engagement with the loop of the next adjoining link, they are held together by 110

this loop and prevented from spreading apart. This serves to prevent the lateral loops α^s which are located adjacent to these eyes, from spreading apart under any lateral strains to which they may be subjected by reason of their engagement with the transverse connecting links B.

The frame to which the fabric is secured may be of any suitable construction and the fabric may be secured thereto in any desirable manner. The frame shown is composed of the usual angle iron side and end rails C and D and the fabric is secured to the end rails by suitable springs E which connect the end links in the longitudinal rows of links to the end rail.

The modified form of link, shown in Fig. 3, differs from the construction above described in that the lateral loops are closed instead of having open ends through which the closed hooks of the transverse links can be inserted. This is done by bending the side bars α^2 of the link over upon themselves or twisting them to form lateral extending closed loops or eyes α^4 . When these links are used it is necessary to leave the hooked ends b of the transverse links open until they are hooked into the loops α^4 and then close them by any suitable means.

Both the longitudinal and transverse links can be economically manufactured, and easily and quickly assembled to form the fabric. When assembled, they will turn freely on each other but cannot become disconnected or shift their positions upon each other. By providing each link with separate loops and eyes for engagement with the adjacent longitudinal and transverse links, independent connections are formed which permit the longitudinal and transverse links to move freely relative to each other. The fabric is simple in construction, neat in appearance and at the same time possesses great strength and is very flexible.

I claim as my invention:

1. A bed-bottom fabric composed of longitudinal and transverse links connected together longitudinally and transversely of the fabric, each longitudinal link consisting of a wire bent upon itself to form two substantially parallel bars having a loop at one end of the link and eyes at the opposite end of the link, said link having opposite laterally projecting loops adjacent to its eyes for engagement with said transverse links, and the

eyes of said link engaging the end loop of the next adjoining longitudinal link and being held thereby from lateral separation, substantially as set forth.

2. A bed-bottom fabric composed of longitudinal and transverse links connected together longitudinally and transversely of the fabric, each longitudinal link consisting of a wire bent upon itself to form two substantially parallel bars which extend side by side and are connected together at one end by a loop and terminate at the opposite end of the link in separate eyes, said bars being provided adjacent to said eyes with opposite laterally projecting loops for engagement with said transverse links and said eyes engaging the end loop of the next adjoining link and being held thereby from lateral separation, substantially as set forth.

3. A bed-bottom fabric composed of longitudinal and transverse links connected together longitudinally and transversely of the fabric, each longitudinal link consisting of a wire bent upon itself to form two substantially parallel bars which extend side by side and are connected together at one end by a loop and terminate at the opposite end of the link in separate eyes, each of said bars being provided adjacent to its eye with an open loop which projects laterally from said link for engagement with a transverse link, the eyes of said bars engaging the end loop of the next adjoining link and being held thereby from lateral separation, substantially as set forth.

4. A bed-bottom fabric composed of longitudinal links and transverse connecting links, each of the longitudinal links consisting of a wire bent upon itself to form two substantially parallel bars having a loop at one end of the link and eyes at the opposite end of the link for connecting said links together end to end, said link having opposite laterally projecting loops adjacent to its eyes for engagement with said transverse links and said loops having contracted throat portions for retaining said transverse links in engagement therewith, substantially as set forth.

Witness my hand in the presence of two 105 subscribing witnesses.

EDWARD NICKERSON.
